UNITED STATES PATENT OFFICE

WILLIAM J. DAUBENSPECK, OF CLEVELAND, OHIO, ASSIGNOR TO THE IGNITION MANUFACTURING COMPANY, OF CLEVELAND, OHIO, A CORPORATION OF OHIO

SPARK PLUG

Original application filed December 30, 1925, Serial No. 78,362. Divided and this application filed November 1, 1927. Serial No. 230,292.

The subject matter of this application is divided out of my pending application Serial No. 78,362, filed December 30, 1925, upon improvements in spark plugs.

My invention particularly relates to spark plug structures for internal combustion engines having automatically-operating sliding valves for admitting air for cleansing and cooling and for mixture with the explosive charge.

10 The annexed drawing and the following description set forth in detail certain means embodying my invention, such disclosed means, however, constituting but two of the 15 various forms in which the principle of the invention may be illustrated.

In said annexed drawing:

Figure 1 is a longitudinal sectional view, partially in elevation, of my improved spark 20 plug, showing therein one form of an improved valve and valve support;

Figure 2 is a transverse horizontal section, taken in the plane indicated by the line 2—2, Figure 1;

25 Figure 3 is a plan view of the elements shown in Figure 1, certain parts being removed;

Figures 4 and 5 are detailed views of the 30 form of valve and valve support shown in Figure 1, the valve support being omitted in Figure 5; and

Figures 6 and 7 are detailed views of a modified form of valve and valve support.

As pointed out in my application, Ser. No. 35 78,362, from which the subject matter of this application has been divided out, and referring to the annexed drawing in which the same parts are designated by the same respective ordinals in the several views, an

40 annular spark plug shell or body member 5 is formed with a hexagonal top portion 6 and a lower externally-threaded plug portion 7 carrying a grounded L-shaped electrode 8 providing a spark gap with the electrode 9 mounted in the insulating porcelain

45 10, the latter having an inner reduced extension 12 in the bore 13 of the body 5 to form an annular chamber 15. The porcelain member 10 is concentrically secured in the body 5 by a nut 11 engaging an internally-threaded

wall in the top portion 6 of the body 5. As shown in Figures 1, 2 and 3, valve inlets 14 are angularly disposed in the body 5 and communicate with the chamber 15 at their inner ends and at their outer ends communicate with chambers 28 disposed intermediately the air inlets 14 and the other inlets 24 extending to the outer surface of the plug body portion 6. These inlets 24 are of a larger cross-section than the inlets 14 and contain the stems 22 of valves having heads 21 adapted to seat upon the outer wall portions 29 of the chambers 28 and adapted to be reciprocated between the inner wall portions 30 of said chamber and said seat portions 29. As noted, the valve head 21 comprises the inwardly flaring portion 21' and the enlarged inner portion 31, the latter of which is formed with a transverse slot 23 permitting air to pass into the inlets 14 by the valve head 21 when the latter is in its open position and in contact with the inner wall portion 30. The valve is contained within an annular cage or valve support 20 press-fitted into openings 32 formed in the top of the body 75 portion 6. The piston suction stroke opens the valves and permits suction drawn jets of cleaning and cooling air to be directed against the porcelain 10 and to whirl in the chamber 15 and about the electrodes 8 and 9. The piston compression stroke closes the valves upon the seats 29. An outer annular groove 17 formed in the porcelain 10 and connecting spiral grooves 18 cooperate to deflect and whirl the air in the chamber 15. 80

The ordinary electrode insulating porcelain is made relatively large to carry off heat from combustion; whereas, the air cooled and air cleaned porcelain herein shown may be made relatively small.

90 In the form of valve structure shown in Figures 6 and 7, the valve support 25 is screw-threaded as at 26 for the purposes of adjustably securing the same in the valve body 5, the outer face of the cage 25 being formed with transverse slots 27 to receive a screw-driver, the valve head portion 31 also being formed with the transverse slot 23 to permit, as is also true of the form of valve shown in Figures 4 and 5, the adjustment, 100

from the inside, of the valve head 21 to its seat 29. In this form of device, the cage 25 is extended inwardly to cover the full length of the valve head 21 and to abut the bottom 5 wall of the body opening 32, as plainly indicated by the reference characters 33, this bottom wall serving to stop the suction-drawn inward movement of the valve.

It will be noted from the foregoing description that the reciprocating valves are 10 formed with longitudinally-extending peripheral portions 22 and 31 which are spaced from the walls of the air openings formed in the cages 20 and 25 and other peripheral portions 21' which are adapted, in the open position of the valve, to be spaced from the walls of said air openings and, in the closed position of the valve, to be seated on said walls.

This form of spark plug and valve may be 20 manufactured very economically, the valve members adding only slightly to the cost. When used as an air valve in connection with the operation of spark plugs of internal combustion engines, the suction stroke of the piston 25 causes the automatically reciprocating valve portion to assume its open position shown in Figures 1 and 6 and thus permit air to be drawn into the spark plug to be mixed with the fuel obtained from the carburetor. 30 When the piston is moved upwardly in the cylinder, the compression moves the valve to its closed position, shown in Figure 4, thus shutting off communication through the valve supports 20 and 25. When the valve is in its 35 open position, its inner face 34 is adapted to contact with the bottom wall of the body structure 5 within which the cage 20 or 25 is secured, so that provision for the passage of air from the space 24 to the space 14 is made 40 through the medium of the transverse channel 23 formed in the inner face of the valve portion 31. The outer portion of the valve stem 22 projects somewhat beyond the face of the valve support 20 or 25 so as to permit inspection of the valve operation from the outside of the spark plug body. This outwardly-extending valve end portion also permits the valve to be held open by pressing against this projecting end, whereby the valve seat and channels can be cleaned by applying hot gases therethrough and whereby the valve can be tested. Also, by means of this projecting valve end, the valve can be agitated if it shows a tendency to stick.

An economically produced valve of long life and sensitive satisfactory operation is obtained by the means hereinbefore described and shown in the accompanying drawing, and when the said valve structure is used in connection with the operation of spark plugs in internal combustion engines, the result is to obtain a leaner combustible mixture which is even more effective than a richer mixture in the same engine not provided with my improved air valve, effecting a very valuable

saving in fuel cost and a material reduction of the combustible fuels in the exhaust, resulting also in the following other favorable results: providing air for the cylinder mixture to more completely burn the less combustible vapors in the cylinder; providing a surplus of oxygen, especially at the spark plug to insure complete combustion of all carbon at this point; maintaining the spark plug clean and cool; removing accumulated carbon from the engine piston tops and the valve tops and the manifold; obviating short-circuiting of the ignition current; avoiding pre-ignition; greatly improving the quick pickup and power and general operation of the engine; and greatly reducing the work and time necessary to start a cold engine.

What I claim is:

1. An improved spark plug construction comprising a shell and an insulator therein with an annular space between the insulator and the shell, an open-ended cage fitted in the outer wall of said shell and adapted to form a valve support, a reciprocating valve member disposed in the chamber of said support and formed with longitudinal peripheral portions spaced from the walls of said chamber and other peripheral portions adapted in the inner position of said valve member to be spaced from the walls of said chamber and in the outer position of said valve member to be seated on said walls, and a passage communicating with the interior of said cage and said annular space, said passage being formed with an outer enlarged portion of greater longitudinal magnitude than the length of the seating portion of said valve member to permit the reciprocation of the latter, the outward movement of said member closing said passage by the seating of the valve member on said cage walls, said insulator being formed with outer peripheral grooves adjacent said annular space for producing a whirling action of the air within the shell.

2. An improved spark plug construction comprising a shell and an insulator therein with an annular space between the insulator and the shell, an open-ended cage fitted in the outer wall of said shell and adapted to form a valve support, a reciprocating valve disposed in the chamber of said support and formed with longitudinal peripheral portions spaced from the walls of said chamber, an intermediate connecting diagonal surface portion adapted in the inner position of said valve to be spaced from the walls of said chamber and in the outer position of said valve to be seated upon said walls, and a passage communicating with the interior of said cage and said annular space, said passage being formed with an outer enlarged portion of greater longitudinal magnitude than the length of the seating portion of said valve member to permit the reciprocation of the

- latter, the outward movement of said member closing said passage by the seating of the valve member on said cage walls, said insulator being formed with outer peripheral grooves adjacent said annular space for producing a whirling action of the air within the shell. 5
3. A spark plug comprising a shell and an insulator therein with a substantial annular space between the insulator and the shell, said shell having a valved passage leading from the exterior surface of the shell to said annular space and said insulator being provided with a groove in a portion of its surface forming one wall of said annular space. 10
- 15 4. A spark plug comprising a shell and an insulator therein with a substantial annular space between the insulator and the shell, said shell having a valved passage leading from its exterior surface to said annular space and said insulator being provided with a groove in a portion of its surface situated in line with said passage. 20
- 25 5. A spark plug comprising a shell and an insulator therein of such size and form as to provide a substantial annular space between the insulator and the shell, said shell having a valved passage leading from its exterior surface to said annular space and said insulator being provided with grooves in a portion of its surface situated below said passage. 30
- 35 6. A spark plug comprising a shell and an insulator having a portion within said shell of such size and form as to provide a substantial annular space between the insulator and the shell, said shell having a valved passage leading angularly through the shell from its exterior surface to said annular space and said insulator being provided with grooves in a portion of its surface situated below and in line with said passage. 40
- 45 7. A spark plug comprising a shell and an insulator having a portion within said shell of such size and form as to provide an annular space between the insulator and the shell, said shell having a valved passage leading angularly through the shell from its exterior surface to said annular space and said insulator being provided with a spiral groove in line with said passage. 50
- 55 8. A spark plug comprising a shell and an insulator having a portion within said shell of such size and form as to provide a substantial annular space between the insulator and the shell, said shell having a valved passage leading from its upper exterior surface to said annular space and said insulator being provided with grooves in a portion of its surface forming one wall of said annular space and situated below said passage. 60
- 65 9. A spark plug comprising a shell and an insulator having a portion within said shell of such size and form as to provide an annular space between the insulator and shell, said
- shell having a valved passage leading angularly from its upper exterior surface to said annular space and said insulator being provided with a spiral groove in a portion of its surface forming one wall of said annular space and in line with said passage. 70
10. A spark plug comprising a shell and an insulator therein of such size and form as to provide a substantial annular space between the insulator and the shell, said shell having a plurality of valved passages leading angularly from its exterior surface to said annular space and said insulator being provided with a plurality of spiral grooves in line with said passages. 75
11. A spark plug comprising a shell and an insulator therein of such size and form as to provide an annular space between the insulator and shell, said shell having a plurality of valved passages leading from its exterior surface to said annular space and said insulator being provided with annular and spiral grooves below said passages. 80
12. A spark plug comprising a shell and an insulator having a portion therein of such size and form as to provide an annular space between the insulator and the shell, said shell having a passage leading from its exterior surface to said annular space, said passage being adapted to permit the entry of fluids into the spark plug and to prevent the escape of gases from the spark plug, and said insulator being provided with a spiral groove near said passage. 85
13. A spark plug comprising a shell and an insulator having a portion therein of such size and form as to provide an annular space between the insulator and the shell, said shell having passages leading from its exterior surface to said annular space, said passages being adapted to permit entry of fluids into the spark plug and to prevent the escape of gases from the spark plug, and said insulator having annular and spiral grooves near said passages. 90
14. A spark plug comprising a shell and an insulator having a portion therein of such size and form as to provide an annular space between the insulator and the shell, said shell having a passage adapted to permit the passage of fluids into the annular space and said insulator being provided with a groove in a portion of its surface forming one wall of said annular space and near said passage. 95
15. A spark plug comprising a shell and an insulator having a portion therein of such size and space as to provide an annular space between the insulator and the shell, said shell having a passage adapted to permit entry of atmospheric air into the annular space when the pressure in the annular space is reduced below atmospheric pressure and said insulator being provided with a groove in a portion of its surface forming one wall of said annular space and below said passage. 100
- 110
- 115
- 120
- 125
- 130

16. In a spark plug, the combination with a shell having a valved passage leading from its exterior surface to its interior surface, of an insulator having a portion of such size and form within the shell as to provide a substantial annular space between the insulator and the shell, said insulator being provided with a spiral groove in a portion of its surface forming one wall of said annular space and situated near said passage.
17. In combination with a substantially cylindrical shell having a valved passage leading from its exterior surface to its interior surface, an insulator having a portion of such size and form within the shell as to provide a substantial annular space between the insulator and the shell and having an annular groove in a portion of its surface forming one wall of said annular space and situated near said passage.
18. In combination with a substantially cylindrical shell having a valved passage leading from its exterior surface to its interior surface, an insulator having a portion of such size and form within the shell as to provide a substantial annular space between the insulator and the shell and having annular and spiral grooves in a portion of its surface forming one wall of said annular space and situated near said passage.

Signed by me this 31st day of October,
1927.
